ABSTRACT

A luminaire having a holder for Pisello-lamps comprising two laterally projecting studs around which the connection wires of the lamp are wound and which can be contacted with the contact elements of the plate.

4 Claims, 2 Drawing Figures

PATENTED FEB 4 1975

3,864,006

LUMINAIRE HAVING A HOLDER FOR A CAPLESS MINIATURE INCANDESCENT LAMP

The invention relates to a luminaire having a holder for a capless miniature incandescent lamp which comprises connection wires projecting outwards on one side for the connection to a plate which is provided with contact elements.

From German published Pat. application No. 1,589,314 such a luminaire is known in which the lamps are provided at their necks with ribs which lock in a circumferential groove of the lampholder. Although this results in a comparatively rigid connection between the lamp and the lamp holder, said construction requires specially shaped lamps and correspondingly shaped holders. The connection wires of the lamps are clamped between the holder and the plate when the holder is clamped to the plate. For that purpose, however, the connection wires of the lamp must be comparatively thick since otherwise they might break during the rotary movement required to connect the holder.

For instrument and dial lighting, for example, in wireless sets, very small miniature incandescent lamps having ninepin-shaped envelopes, so-called Pisello-lamps, are used. Such Pisello-lamps have no ribs with which they can be locked in a holder. It is the object of the invention to provide a holder for such lamps which, as compared with the said known luminaires, is much simpler and cheaper of construction and in which the fact that the connection wires of Pisello-lamps are very thin and, mechanically, can be loaded only restrictedly, has been taken into account.

According to the invention, in a luminaire of the above-mentioned type this is achieved in that the holder comprises two laterally projecting studs around which the connection wires of the lamp are wound and which are connected to the contact elements of the plate. So in this case the connection of the lamp in the holder occurs by means of the connection wires of the lamp in that said connection wires are wound around two laterally projecting studs. Upon securing the holder to a plate, the studs wound in this manner are contacted with the contact elements present on said plate.

According to a favourable embodiment, the luminaire according to the invention is characterized in that the contact elements of the plate are in the form of leaf springs below which the studs of the lampholder (around which the connection wires of the lamp are wound) are slid. In that case, the leaf springs serve not only for making an electric contact but also for securing the lampholder to the plate.

However, said plate may also comprise a recess in which a projection of the holder engages in a locking manner. In that case the plate may be provided, near the studs, with metal contact faces which replace the above-mentioned leaf springs.

The invention will now be described in greater detail with reference to two embodiments shown in the drawing.

FIG. 1 is a perspective view of a luminaire according to the invention in which the connection of the holder to the plate as well as the electric contact has been realized by means of leaf springs.

FIG. 2 shows another embodiment of the luminaire according to the invention in which the electric contact has been realized by means of contact faces.

The luminaire serves to receive a Pisello-lamp 1 which is provided in a holder 2 of a synthetic material or the like. The holder 2 consists of a member 3 having two upright supports 4 between which the wide end of the lamp 1 is incorporated. The member 3 comprises two slots 6 which extend in the axial direction of the connection wire 5 of the lamp and parallel to the edge of the holder up to the centre of the holder. In the region of the member 3, the holder 2 comprises two laterally projecting studs 7.

For connecting the lamp in the holder 2, the lamp is placed between the supports 4, the connection wires 5 are then introduced into the slots 6, stretched taut and then routed to the laterally projecting studs 7 to be secured there by winding around the studs 7. The ends of the connection wires 5 of the lamp wound around the studs are denoted by 8.

The holder 2 with the lamp 1 is now to be secured to a plate 9. For that purpose, two leaf springs 10 which serve as contact elements are provided on the plate 9 and below said leaf springs the studs 7 of the lampholder 2 (around which the connection wires 5 are wound) are slid. In this case the leaf springs 10 serve as contact elements and for the mechanical connection of the holder 2 to the plate 9.

When one of the leaf springs 10 is rotated through 180° relative to the other leaf spring, the connection of the holder 2 to the plate 9 may be carried out by means of a rotary movement of the holder 2, the studs 7 being slid below the leaf springs 10.

In the luminaire shown in FIG. 2, the front support 4 of the holder 2 comprises a downwardly directed projection 11 which has a T-profile at its end. Furthermore the plate 9 comprises a slot-like recess 12 in which the projection 11 of the holder 2 engages in a locking manner as a result of which a good connection of the holder 2 to the plate 9 is ensured.

The contacting in this case is carried out by means of two strip-shaped contact faces 13, for example in the form of printed conductors, which are provided on the plate 9 in the region of the studs 7 around which the connection wire ends 8 are wound.

What is claimed is:

1. A luminaire having a holder and a capless miniature incandescent lamp, an insulating plate having contact elements disposed thereon and carrying said holder, said holder comprising two upright supports cooperatively dimensioned and configured for holding said lamp, connection wires projecting outwards on one side of said lamp and engaging said contact elements on said insulating plate, said holder further comprising two radially projecting studs around which the connection wires of the lamp are wound and which are connected to the contact elements of the plate.

2. A luminaire as claimed in claim 1, wherein the contact elements of the plate are in the form of leaf springs having a detent therein for sliding engagement with said studs of the lampholder, said studs having the connection wires of the lamp wound thereabout.

3. A luminaire as claimed in claim 1 wherein the plate comprises a recess in which a projection of the holder engages in a locking manner.

4. A luminaire as claimed in claim 3, characterized in that the plate comprises metal contact faces near the studs.
